United States Patent Office

Des. 217,456
Patented May 5, 1970

217,456

FIREPLACE GRATE

Judkins E. Wilkinson, Birmingham, Ala., assignor to
Atlanta Stove Works, Inc., a corporation of Georgia

Filed Nov. 13, 1968, Ser. No. 14,420

Term of patent 14 years

Int. Cl. D23—03

U.S. Cl. D23—98

Fig. 1

Fig. 2

Fig. 3

FIG. 1 is an end elevational view of my fireplace grate, the other end thereof being identical to the end shown;

FIG. 2 is a front side elevational view of my fireplace grate, the other side being substantially identical to the side shown, there being a slight difference in length; and,

FIG. 3 is a top plan view of the fireplace grate;

FIG. 4 is a perspective view of the fireplace grate.

I claim:

The ornamental design for a fireplace grate, as shown and described.
